UNITED STATES PATENT OFFICE.

THOMAS F. CROCKER, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed March 23, 1925. Serial No. 17,539.

This invention relates to telephone systems in general, but is more particularly concerned with automatic telephone systems of relatively small size, commonly known as 5 private automatic exchanges.

A private automatic exchange is usually employed to serve special groups of subscribers, such as in a factory or business organization. Better service is obtained between 10 substations within the organization if the service is given by a private exchange, which obviates the necessity of calling through a central office. Such a private automatic exchange, however, may have access to the central office by means of trunks or groups of trunks, and may also give service to individual common battery telephone substations reserved for officials who desire special service.

15 In such a system it may be required to give restricted service to some substations and unrestricted service to other substations; and it is the principal object of this invention to provide simple and efficient trunk circuits and a new universal cord circuit for the attendant's switchboard for completing the several types of calls and rendering the different kinds of service required.

A special feature of this invention relates to improved circuits which are so arranged as to prevent the attendant from setting up an unauthorized connection between two so-called restricted substations, should she attempt to do so in the ordinary way, by inadvertence or mistake.

A further feature is concerned with means in the attendant's cord circuit which makes it impossible for the attendant to complete an unauthorized connection, either electrically or mechanically, by a combination of cords or keys, should she attempt to do so deliberately, with the object of defrauding the company.

These features of the invention, and others, will be fully described in connection with the explanation of the various operations performed in the private automatic exchange described below, reference being had to the accompanying drawings.

The telephone system illustrated for the purpose of describing this invention consists of a private automatic exchange, one or more associated common battery manual switchboards which are connected with the

private automatic exchange by trunk lines, 55 and several individual common battery telephones whose lines terminate at the private automatic exchange. Trunk lines are also provided from the private automatic exchange to the main automatic exchange. In 60 this system certain restrictions in service are desired. The substations at the private automatic exchange are divided into two classes, one class having restricted service and the other class having unrestricted service. The restricted substations have access to any other private automatic substation and may obtain connection by the attendant through her cord circuit to any of the special common battery substations or to the 70 common battery manual switchboards in the system, but are denied service to the outside main automatic exchange. The substations in the unrestricted class may obtain connection with any substation in the system and 75 also with the main automatic exchange. The common battery substations or the common battery manual boards are not restricted and may obtain connection with any of the private automatic substations or with the 80 main automatic exchange through the attendant's cord circuit. Calls from the central automatic exchange, however, are denied connection to the private automatic substations in the restricted class, but may obtain connection with the unrestricted private 85 automatic substations and also with the common battery substations and common battery manual switchboards.

Referring now to the drawings, the three 90 figures placed end to end in numerical order show enough of the essential elements of the specific telephone system thus briefly described to illustrate and explain the invention. In Fig. 1 are represented two of the 95 private automatic substations, the automatic switches, and the trunk circuits that are brought into operation when a subscriber at a private automatic substation calls the attendant, or the attendant completes a call 100 to a private automatic substation. Fig. 2 is a diagram of the new universal cord circuit at the attendant's position. In Fig. 3 are represented a trunk to a central automatic exchange, a line to a common battery telephone, and a trunk to a common battery manual switchboard, with their respective 105 associated trunk and line circuits.

The apparatus shown in the drawings will now be explained more in detail. The substations A' and A in Fig. 1 are ordinary automatic telephones having lines consisting of conductors 2 and 3, and 4 and 5, respectively. Substation A' is given restricted service while substation A is allowed unrestricted service. Associated with each telephone line at the automatic exchange is an individual line switch, such as the line switches LS or LS' which are individual to substations A and A', respectively, Fig. 1. The line switches are of the common rotary type in which the wipers have no normal position and move in a forward direction only. The total number of line switches is divided into groups, each group having access to a group of selectors. When a call is initiated at a substation, the line switch of that substation operates to select an idle selector in the associated group of selectors.

The selectors, one of which is indicated by reference letter S, Fig. 1, are of the usual Strowger vertical and rotary type, having bank contacts arranged in horizontal rows or levels.

The selectors have access to groups of trunks terminating at the attendant's cabinet and also to groups of connectors. In this particular case it will be assumed that the tenth or zero level is assigned to the group of trunks reserved for service to the main automatic exchange and is accessible only to those substations which have unrestricted service. It is further assumed that the ninth level is assigned to the group of trunks reserved for information service and for calls to the common battery manual switchboard and common battery substations. This group of trunks is accessible to all substations, restricted as well as non-restricted. Means are provided in the selectors, and in the line switches associated with the substations assigned to restricted service, for preventing the restricted substations from obtaining connection with any trunk on the tenth or zero level.

One of the trunks reserved for service to the main automatic exchange is represented by conductors 57, 58, and 59, extending from the tenth level of the selectors and terminating at the attendant's switchboard in the jack J, with its associated trunk circuit TC. The trunk comprising conductors 61, 62, and 63, extending from the ninth level and terminating at the attendant's cabinet in the jack J' with its associated trunk circuit TC', is one of the trunks assigned for information service or service to the common battery telephones or to the common battery manual switchboards.

Each private automatic substation has a multiple jack at the attendant's cabinet, which enables the attendant to complete incoming calls to the private automatic substa-

tions direct. The jack J² is the jack associated with the substation A, while jack J³ is the jack associated with the substation A'.

The attendant's switchboard or cabinet is provided with a plurality of cords, and an operator's head set, the circuits of which are shown in Fig. 2, where they are indicated by reference characters CC and HS, respectively. The answering plug of the cord is labeled P and the calling plug is labeled P'. The usual ringing, listening, and dialling keys are provided. Means are provided in the operator's head set and in the cord circuits which prevent the head set from being connected to more than one cord at one time. Common to the cords is a flash and transmitter cut-off key K² for giving a flash-back signal to a manual operator of the common battery switchboard or for short circuiting the transmitter.

The line from substation B, comprising conductors 217 and 218, Fig. 3, terminating at the attendant's cabinet in the jack J⁵, is a line from one of the individual common battery substations.

Several groups of two way trunks, each group assigned to a common battery manual switchboard associated with the private automatic system, terminate at the attendant's switchboard, each trunk ending in a jack, such as J⁶, with an associated trunk circuit TC⁴. These trunks are accessible at the common battery manual operator's position by way of jacks such as J⁷. Associated with each jack is a drop signal, such as drop 311.

Another group of two-way trunks is provided for the central automatic exchange, each trunk terminating at the private automatic attendant's switchboard in a jack such as J⁴, with an associated trunk circuit such as TC². These trunks are accessible in the central automatic exchange via the banks of connectors, as indicated, and terminate in individual line switches, such as LS², which are of the ordinary rotary type similar to LS and LS'.

Having described the system and the apparatus in general, a more detailed description of the operations performed in setting up calls between various substations will be given. The assumption is first made that a substation which has unrestricted service, such as A, desires connection with one of the individual common battery substations, such as B. The subscriber at A, in order to make the call, lifts his receiver and dials the proper number. Since it has been assumed that the trunks to the attendant reserved for service to the common battery substations are accessible in the ninth level of the selector banks, the number to be dialled will be "9".

When the subscriber at substation A removes his receiver, a bridge is placed across the conductors 4 and 5, thereby completing a

circuit for the line relay 7 of the line switch LS. The line relay 7 energizes and completes a circuit from ground by way of armature 13 and its working contact, winding of switching relay 6, resting contact of armature 15 and said armature, winding of the stepping magnet 8 to battery. At armature 14, the test wiper 19 is connected to the junction of the switching relay 6 and the stepping magnet 8.

In case the trunk upon which the wipers of the line switch are resting is idle, switching relay 6 energizes immediately. Assuming the trunk to be busy, however, switching relay 6 is short circuited from ground on the test wiper 19 and does not energize. Wipers 17-20, inclusive, are rotated step by step in a buzzer-like manner by the action of the stepping magnet 8, which operates from ground on the busy test contacts encountered by the test wiper 19. When an idle trunk is reached, which will be assumed to be the trunk comprising conductors 21-24, inclusive, stepping magnet 8 will cease its stepping action. The switching relay 6, being no longer short circuited, energizes in series with the stepping magnet 8. The stepping magnet 8 does not operate at this time on account of the high resistance of the switching relay 6. The operation of the switching relay 6 opens the test circuit and prepares the holding circuit for itself at armature 11, and at armatures 9 and 12 disconnects the line conductors 4 and 5 from the winding of the line relay 7 and ground, and extends them by way of wipers 17 and 20, contacts 96 and 99, conductors 21 and 24, armatures 39 and 42 and their bank contacts, to the upper and lower windings of line relay 25 of the selector S. Line relay 25 energizes and closes a circuit for the slow-to-release relay 26. Relay 26 energizes and opens the circuit of the release magnet 32 and prepares a circuit for the vertical magnet 30 at armature 35; and at armature 34 places ground on the release trunk 23, thereby closing the usual holding circuit for the switching relay 6 of the line switch before the slow-to-release line relay 7 drops back.

When the subscriber at substantiation A dials the digit 9, the circuit of the line relay 25 is opened a corresponding number of times. Each time the line relay 25 falls back, in response to an interruption, a circuit is closed for the vertical magnet 30 which may be traced from ground by way of armature 41 and its resting contact, armature 33 and its resting contact, armature 35 and its working contact, winding of relay 27, through the winding of the vertical magnet 30 to battery. By the operation of the vertical magnet 30, the switch wipers 48, 49 and 50 are raised opposite the ninth level of bank contacts. The series relay 27 is energized in series with the vertical magnet, retaining

its armature attracted throughout the vertical movement of the switch wipers. As a result, a circuit is closed from ground on the release trunk 23 by way of armature 36 and its working contact, normally closed 70 springs 44¹, off normal spring 44 (which are closed upon the first vertical step), winding of stepping relay 28 to battery. The stepping relay 28 energizes and closes a locking circuit for itself at armature 37, and at armature 38 prepares the circuit for the rotary magnet 31. 75

At the end of the vertical movement, the slow acting relay 27 deenergizes and completes the circuit for the rotary magnet 31 80 at armature 36 and its resting contact. The rotary magnet 31 energizes and advances the wipers 48, 49, and 50 into engagement with the first set of bank contacts in this selected level, and, near the end of its movement, opens the circuit for the stepping relay 28 at interrupter contacts 43. The stepping relay 28 now deenergizes and opens the circuit for the rotary magnet at armature 38. The rotary magnet, in turn, deenergizes and again closes its interrupter contacts 43. In case the trunk terminating in the first set of bank contacts is idle, switching relay 29 energizes immediately. Assuming the trunk to be busy, however, 95 switching relay 29 is short circuited by the ground potential encountered by test wiper 49. Stepping relay 28 will again energize from this same ground potential and close a circuit for the rotary magnet 31 a second 100 time. The switch wipers are thus rotated into engagement with the second set of bank contacts. This alternate operation of stepping relay 28 and rotary magnet 31 continues until an idle trunk is reached, which 105 will be assumed to be the trunk terminating in the bank contacts 54, 55, and 56. Switching relay 29, being no longer short circuited by a ground on the test wiper 49, energizes in series with the stepping relay 110 28. The stepping relay 28, however, does not energize at this time on account of the high resistance of the switching relay 29. The operation of the switching relay 29 opens a point in the test circuit and prepares 115 the holding circuit at armature 40; disconnects ground from armature 33 of the line relay at armature 41; and at armatures 39 and 42 disconnects conductors 21 and 24 from the upper and lower windings of the 120 line relay and connects them by way of wipers 48 and 50 to the upper and lower windings of the line relay 81 of the trunk circuit TC¹, respectively. The line relay 81 closes a circuit for the release relay 83 at 125 its armature 84. Upon energizing, the release relay 83 completes a circuit for the call signal lamp L' at armature 87; places ground on the release trunk 62 at armature 86; and at armature 88 places ground on the 130

working contact of the spring 89 of the jack J'.

In response to the lighting of the call signal lamp L', the attendant inserts the plug P into the jack J', and throws the key K to the listening position. When the plug P is inserted into the jack J', a circuit is closed for the cut-off relay 82 from ground by way of the discriminating relay 103 of the cord circuit CC, sleeve of plug P, sleeve of jack J', winding of the cut-off relay 82 to battery. Cut-off relay 82 energizes and opens the circuit of the lamp L' at armature 85, thereby extinguishing the lamp L'. Inserting the plug P into the jack J' places ground on the sleeve of the jack J' at spring 89 and its working contact. Therefore, the discriminating relay 103 remains deenergized at this time on account of the ground 20 on both ends of its winding.

When the key K is thrown to the listening position, a circuit is closed from ground by way of the resting contact of armature 128 and said armature, the working contact of spring 137 and said spring, upper winding of the lock-up relay 101 to battery. Relay 101 energizes and bridges the attendant's head-set across the heavy talking conductors 153 and 154 at armatures 112 and 114; 25 and at armature 113 closes a holding circuit for itself from ground by way of the lower winding of relay 101, armature 113 and its working contact, working contact of spring 138 and said spring, resting contact of spring 131 and said spring, winding of the slow-to-release relay 108 to battery. Relay 108 energizes and opens the initial energizing circuit of relay 101 at armature 128. By the removal of ground from 30 armature 128, no other cord can be connected to the headset at this time, even though the operator inadvertently or otherwise manipulates the listening key of another cord.

The attendant may now converse with the 45 subscriber at the calling substation A and inquire for the number of the substation with which connection is desired, which has been assumed to be the common battery substation B.

50 Since the line to substation B terminates in the one jack J⁵, the busy or idle condition is indicated to the attendant by a plug of a cord being in or not in the jack J⁵.

Assuming that the line to substation B is 55 idle, the attendant inserts the calling plug P' into the jack J⁵. Inserting the plug P' into the jack J⁵ completes a circuit from ground through the lower winding of switching relay 107 of the cord circuit CC, sleeve of the plug P', sleeve of jack J⁵, through the winding of the cut-off relay 210 to battery. Switching relay 107 energizes and connects its upper holding winding to the conductor 153' at armature 127; closes a 60 circuit for the supervisory lamp L⁴ at armature 124; and at armatures 125 and 126, connects the talking strands of the cord to the tip and ring of the plug P', respectively. The tip of the plug P' is also disconnected from the busy test relay 109 at the normally closed springs controlled by armature 125. The cut-off relay 210 also energizes and disconnects the line relay 211 from the line conductors 217 and 218 at armatures 212 and 213, respectively. 75

The attendant now throws the key K' to the ringing position momentarily to signal the called subscriber at substation B. When the subscriber at substation B removes his receiver, a bridge is placed across the line 80 conductors 217 and 218, thereby closing a circuit for the battery feed relay 106. Relay 106, upon energizing, opens the circuit for the supervisory lamp L⁴ at armature 123, thereby extinguishing the lamp L⁴. 85 This indicates to the attendant that the called party has answered. The subscribers may now hold conversation.

At the termination of the conversation, 90 both subscribers will replace their receivers. Replacing the receiver at the substation B opens the bridge across the conductors 217 and 218, thereby opening the circuit for the battery feed relay 106. Relay 106 releases and again closes the circuit for the supervisory lamp L⁴. The lamp L⁴ is again lighted indicating to the attendant that the called party has replaced his receiver. 95

When the receiver at substation A is replaced, the bridge across conductors 4 and 5 100 is opened, thereby opening the circuit of the line relay 81 of the trunk circuit TC'. The line relay 81 deenergizes and opens the circuit for the release relay 82. Relay 83 deenergizes and removes ground from the 105 holding conductors 62 at armature 86, and also removes ground from the working contact of spring 89 at armature 88. The discriminating relay 103 of the cord circuit CC is no longer shunted by ground on both ends 110 of its winding, and therefore operates in series with relay 82. The function of the operation of relay 103 at this time is to close the circuit of the supervisory lamp L³ at armature 116. The lighting of the lamp 115 L³ indicates to the attendant that the calling subscriber at substation A has also replaced his receiver. The attendant is thus signalled by a separate lamp when either the calling subscriber or the called subscriber 120 replaces his receiver, thereby giving what is commonly known as double-lamp switchhook supervision.

The removal of ground from conductor 62 removes the holding ground from conductor 125 23, breaking the holding circuit of relay 29 of the selector S, and also of the switching relay 6 of line switch LS. Switching relay 29, upon deenergizing, closes a circuit for the release magnet 32 from ground by way 130

of armature 41 and its resting contact, armature 33 and its resting contact, armature 35 and its resting contact, closed off normal springs 45, through the winding of the release magnet 32 to battery. The release magnet 32 energizes and restores the selector back to normal.

When the operator receives the signals to release the connection by the lighting of lamp L³ and also L⁴, she removes the plugs P and P' from the jacks J' and J⁶, respectively. The circuits for the discriminating relay 103 and for the switching relay 107 of the cord circuit CC, and for the cut-off relay 82 of the trunk circuit TC' are thereby opened, and all the apparatus is restored to normal.

The assumption is now made that the subscriber at the substation A desires connection with a certain subscriber whose line terminates at one of the common battery manual switchboards. The subscriber at substation A will call the attendant in the manner identical with that described hereinbefore, the call extending through the line switch LS, a selector, such as S, over a trunk terminating in a jack at the attendant's position, such as jack J¹. In response to the lighting of the call signal light, the attendant inserts the answering plug P into the answering jack and throws the key K into the listening position, and inquires for the number of the substation with which connection is desired. After receiving this information, the attendant inserts the calling plug P' into the jack of an idle trunk extending to the proper common battery manual switchboard. It will be assumed that the trunk comprising conductors 229 and 230 accessible at the jack J⁶ and terminating in the common battery manual switchboard at the jack J⁷, is the trunk selected.

Inserting the plug P¹ into the jack J⁶ completes a circuit for the switching relay 107 and the cut-off relay 250 in series. Relay 107 operates and connects the talking strands to the tip and ring of the plug P¹, respectively, and closes a circuit for the supervisory lamp L⁴. Relay 250 operates and disconnects the line relay 251 from the talking conductors 227 and 228 of the trunk circuit TC⁴, at armatures 254 and 255, respectively.

The attendant may now throw the key K to the ringing position for a short interval, thereby actuating the drop signal 311 at the common battery manual switchboard. In response to this signal the manual operator will insert the answering plug of a cord into the jack J⁷. Battery potential on the sleeve of the manual operator's cord will energize the cut-off relay 310, thereby opening the circuit for the drop signal 311 at armature 312. Inserting the answering

plug into the jack J⁷ also completes a circuit for relay 253, there being ground and battery potential on the tip and ring of the manual operator's cord, respectively. Relay 253 operates and closes a bridge including the winding of the polarized relay 252 across conductors 227 and 228 at armature 258. This closes a circuit for the battery feed relay 106 and the polarized relay 252, in series. Relay 106 operates and opens the circuit for the supervisory lamp L⁴ at armature 123. The extinguishing of the lamp L⁴ signals the attendant that the manual operator has answered the call. The polarized relay 252 operates and short circuits the greater portion of the winding of the relay 253 at its armature 257. As a result, the current flow in conductors 229 and 230 is increased sufficiently to operate the supervisory signal in the manual operator's cord. This latter operation has utility in disconnection and in a call originated by the manual operator which is to be described hereinafter. The attendant may now converse with the manual operator, informing her of the connection desired, after which she may restore the key K to normal and proceed to complete other calls or perform other duties.

If for any reason the manual operator is unable to complete the desired connection, she may so inform the calling subscriber directly. It is assumed, however, that the manual operator completes the desired connection, after which the two subscribers hold conversation.

After the termination of the conversation, both the automatic subscriber and the called manual subscriber replace their receivers. When the automatic subscriber replaces his receiver, the lamp L³ of the attendant's cord CC is lighted as previously described. In the call being described, the attendant at the private automatic exchange is the originating operator and therefore removes the plugs P and P' from the jacks J¹ and J⁶, respectively, in response to the lighting of the one lamp L³. Removing the plug P' from the jack J⁶ opens the circuit for the sleeve relay 250. Relay 250 deenergizes and closes a circuit including the bridge across conductors 227 and 228, armatures 254 and 250 and their resting contacts, the upper and lower windings of line relay 251 to battery and ground, respectively. It will be noted that the relay 251 feeds battery potential to the tip side of the line and ground potential to the ring side of the line, which is the reverse of the battery feed as was supplied by relay 106 of the cord CC. The polarized relay 252 is caused to drop back and open the short-circuit from the major portion of the winding of relay 253. This reduces the current flow in conductors 229 and 230 sufficiently to light a supervisory lamp in the

5 manual operator's cord circuit, thereby giving the manual operator the usual disconnect signal. In this kind of call, i. e., from the private automatic exchange to the manual exchange, it is usual for the manual operator to wait for the disconnect signal from the private automatic exchange attendant before pulling down the connection. Should the manual operator remove her plug from 10 jack J^7 before she receives the disconnect signal, the private automatic exchange attendant receives the additional signal by the lighting of lamp L^4 , as will be explained hereinafter.

15 As has been stated before, substations in the unrestricted class, such as substation A, are allowed outside service; i. e., service to the main automatic exchange. It will now be assumed that the subscriber at substation 20 A desires connection with a subscriber in the main automatic exchange. In order to originate such a call, the subscriber at substation A must call the operator by removing his receiver and dialing the digit "0", 25 it being remembered that trunks to the attendant's switchboard reserved for outside service are accessible in the tenth level of the selector banks. When the calling subscriber at substation A removes his receiver, 30 a bridge is placed across the conductors 4 and 5, which completes the circuit for the line relay 7 of the line switch LS. Line switch LS operates in the hereinbefore described manner to select a trunk to an idle selector switch. Assuming the trunk comprising conductors 21-24, inclusive, is the 35 trunk selected, the line relay 25 and the release relay 26 of the selector S energize and prepare the selector for operation.

40 In response to the digit "0" dialed by the subscriber, the selector raises its wipers opposite the tenth level, and then rotates its wipers to select an idle trunk extending to the attendant's switchboard.

45 Assuming that the trunk comprising conductors 57, 58, and 59 is the trunk selected, a circuit is closed for the line relay 75 of the trunk circuit TC, which may be traced from ground by way of armature 80 and its resting contact, conductor 59, over the talking loop to conductor 57, resting contact of armature 79 and said armature, through the winding of the relay 75 to battery. Relay 75 operates and closes the circuit for the call 50 signal lamp L at armature 77 and its working contact, and places ground on the holding conductor 58 at armature 78 and its working contact. In response to the lighting of lamp L, the attendant inserts the plug P into the jack J and throws the key K in the listening position, thereby bridging the attendant's headset across the talking strands of the cord circuit. Inserting the plug P into the jack J, completes the 55 circuit for the cut-off relay 76 and the dis-

criminating relay 103 in series. Relay 76 operates to open the circuit of relay 75 at armatures 79 and 80. Relay 75, upon de-energizing, opens the circuit for the call signal lamp L at armature 77 and removes the 60 initial ground from the holding conductor 58 at armature 78. A holding ground is supplied to conductor 58 at armature 80 before the line relay 75, being slow acting, has had time to fall back. The discriminating relay 103 operates and places ground on the discriminating conductor 153 at armature 116 and its working contact, and at armatures 117 and 118 and their working contacts bridges the battery feed relay 102 so across the talking strands 153 and 154 of the cord circuit. Relay 102 operates and opens the circuit for the supervisory lamp L^3 at armature 115, thereby preventing this lamp from lighting at this time. The attendant 85 now converses with the calling subscriber and is informed of the number of the substation with which connection is desired. Having received this information, the attendant inserts the plug P' into a jack of 90 an idle trunk extending to the automatic exchange. It will be assumed that the trunk comprising conductors 207 and 208 accessible at the jack J^4 is the trunk selected.

95 Inserting the plug P' into the jack J^4 closes a circuit from ground through the winding of relay 107, sleeve of plug P', sleeve of jack J^4 , through the winding of the cut-off relay 201 to battery. Ground potential is also placed on 100 the sleeve of jack J^4 at the working contact of spring 206, thereby preventing the operation of relay 107 at this time. Cut-off relay 201 operates and opens a point in the circuit of the supervisory lamp L^5 at armature 203, and connects conductor 208 to the ring of jack J^4 at armature 204 and its working contact, thereby also disconnecting the ring-down relay 202 from conductor 208.

110 After inserting the plug P' into the jack J^4 , the attendant throws the key K' into the dialling position. A circuit is thereby closed for the switching relay 107 from ground on the discriminating conductor 153', working contact of spring 146 and said 115 spring, through the winding of relay 107 to battery. Relay 107 operates and closes a holding circuit for itself at armature 127 and its working contact; connects the talking strands of the cord CC to the tip and ring 120 of the plug P', at armatures 125 and 126, respectively; and at armature 124 closes a circuit for the supervisory lamp L^4 , thereby 125 also closing the polarizing circuit for the upper winding of relay 105. The attendant's dial D is now bridged across the tip and ring of the plug P at springs 143 and 144 and their working contacts. A circuit is also closed at spring 145 and its working contact for relay 104. Relay 104 operates 130

and closes a locking circuit for itself at armature 121, and at armatures 119 and 120 bridges the lower winding of the polarized relay 105 across the talking strands 151 and 150 of the cord circuit CC.

When the key K' is thrown to the dialling position, thereby bridging the dial D across the tip and ring of the plug P', a circuit is closed for the line relay of the line switch LS² at the distant main automatic exchange. The line switch LS² operates and selects the trunk to an idle selector, the manner of operation being similar to that of line switch LS described hereinbefore. Assuming the trunk comprising conductors 301, 302, and 303 is the trunk selected, the line and release relays of a corresponding selector operate to prepare the said selector for operation and also ground the release trunk 302, thereby completing the holding circuit for the switching relay of the line switch LS². In response to the digits dialled by the attendant, this selector, and possibly others, as the case may be, and a connector, operate to extend the connection to the desired substation and ring the bells. After dialling the number of the called station, the operator restores the key K'.

When the called automatic subscriber removes his receiver to answer the call, the direction of current over the calling trunk is reversed by the operation of the back bridge relay of the connector switch at the main automatic exchange, as is well known in the art. This reversal of current causes the polarized relay 105 of the cord circuit, which is now bridged across the calling trunk conductors 207 and 208, to operate and open the circuit for the supervisory lamp L⁴ at armature 122. The extinguishing of the lamp L⁴ indicates to the attendant that the called automatic subscriber has answered and that the two subscribers are holding conversation.

When the conversation is completed, both subscribers will replace their receivers. When the called subscriber replaces his receiver, the direction of current flow over the calling trunk and, therefore, in the lower winding of the polarized relay 105 is reversed back to normal by the de-actuation of the back bridge relay in the connector switch. Relay 105 falls back and again closes the circuit for the supervisory lamp L⁴ at armature 122. The lighting of lamp L⁴ signals the operator that the called subscriber has replaced his receiver.

When the calling subscriber at substation A replaces his receiver, the bridge across the heavy talking strands is opened, thereby opening the circuit for the battery feed relay 102 in the cord circuit. Relay 102 deenergizes and again closes the circuit for the supervisory lamp L³ at its armature

115. The lighting of lamp L³ signals the attendant that the calling subscriber has replaced his receiver.

The lighting of both lamp L³ and lamp L⁴ is the disconnect signal for the attendant, in response to which she removes the plugs P and P' from the jacks J and J⁴, respectively. Removing the plug P' from the jack J⁴ opens the circuit for the cut-off relay 201, and opens the holding bridge across the conductors 207 and 208. The selectors and connectors in the main automatic exchange are now released in the usual manner. Ground is removed from the holding conductor 302, thereby opening the holding circuit for the line switch LS², restoring it to normal.

Removing the plug P from the jack J opens the circuit for the cut-off relay 76 and the discriminating relay 103. Relay 103 de-energizes and removes ground from the discriminating conductor 153' at armature 116. The removal of ground from the discriminating conductor 153 opens the holding circuit of the switching relay 107, and opens the circuit for the lamp L³. Relay 107 falls back and opens the circuit for lamp L⁴ and the polarizing winding of relay 105, at armature 24 and disconnects the talking strands from the tip and ring of the plug P' at armatures 125 and 126, respectively. Relay 76 deenergizes and removes ground from the holding conductor 58 at armature 80. The removal of ground from the holding conductor 58 causes the release of the selector S and the line switch LS in the manner described hereinbefore.

In the foregoing descriptions, the operations for completing connections from a substation in the unrestricted class to a substation at the main automatic exchange, to one of the individual common battery telephones, and to a substation of one of the common battery manual switchboards are described. As previously mentioned in the beginning of this specification, the substations having restricted service may also obtain connection with any of the individual common battery telephones or with any of the substations of the common battery manual switchboards. Connection between a restricted substation such as A' and an individual common battery substation, such as B, may be extended by way of the line switch LS' individual to the substation A', a selector, such as S, over a trunk terminating at the attendant's switchboard in a jack, such as J', whence the attendant may complete the connection by means of a cord CC, to the jack J⁵, which is individual to the line to the substation B. The various operations performed by the attendant and also by the automatic switches are identical to those hereinbefore described in completing a connection from the substa- 130

tion A to the substation B. Likewise a connection may be completed from a restricted substation to any of the substations of a common battery manual switchboard in a manner identical to the manner in which a connection is completed from the substation A to any of the substations of the common battery manual switchboard.

In order to further bring out the features of this invention, it will now be assumed that the subscriber at substation A' attempts to obtain connection with a substation at the main automatic exchange. It will be remembered that since the substation A' is assigned to restricted service, this connection is not to be granted. In the following descriptions, it will be shown how any attempts to complete an unauthorized connection will fail. In an attempt to obtain such a connection, the subscriber at A' may either dial the digit "0," it being remembered that trunks to the operator's position reserved for service to the main automatic exchange are accessible in the tenth level of the selector banks, or he may dial the digit 9, thereby completing a connection with the operator in the manner previously described and then instruct the operator to complete the connection desired. It will be assumed first that the former attempt is made. When the subscriber at A' removes his receiver, a bridge is placed across conductors 4 and 5, which completes a circuit for the line relay 6 of the line switch LS. The line switch LS', as described before, operates to select a trunk to an idle selector. Assuming the trunk comprising conductors 21-24, inclusive, is the trunk selected, the line relay 25 and the release relay 26 of the selector S, energize and prepare the selector for operation.

The subscriber at A' now dials the digit "0". In response to the impulses produced, the selector raises its wipers opposite the tenth level of bank contacts. When the shaft supporting the wipers is raised to the tenth level, the shaft springs 96' are closed, thereby placing ground upon the test wiper 49 by way of jumper 16, working contact of armature 10', and said armature, wiper 18' and contacts 97', closed springs 96', to wiper 49. It will be remembered that a busy trunk is denoted by ground upon the test contact. Therefore, when the selector begins its rotary trunk selecting movement, in effect all trunks will test busy, and the wiper will be rotated over the entire level to the eleventh contact set. On the eleventh rotary step the cam 94 opens the circuit of the stepping relay 28 at the springs 44', and also closed the springs 46 and 47, thereby removing the original ground from the lower winding of the line relay 25, and substituting the ground from the busy machine B. The busy tone is thereby superimposed upon the conductors 24 and 21 which indicates to the subscriber

at substation A' that the attempted connection is not being completed.

The method employed to restrict the service at any substation now becomes evident. In the individual line switch of any restricted substation, for example, the line switch LS' of the substation A', ground is connected to the working contact of the armature 10' by means of the jumper 16. Direct ground is thereby placed on the test wiper of the selector whenever the shaft springs 96' are closed, the assumption in this case being that they are closed when the selector shaft is raised to the tenth level. In the individual line switches of the substations granted unrestricted service, for example, line switch LS of the substation A, no ground is connected to the working contact and armature 10, the jumper being omitted. Consequently, the armatures corresponding to armature 10 and the wipers corresponding to wiper 18 have no function on these line switches, and the unrestricted substations can obtain connection on all levels of the selectors.

It will now be assumed that the subscriber of the restricted substation A' attempts to obtain connection to a subscriber in the main automatic exchange by calling the operator in the usual way by dialling the digit 9 and then requesting the desired connection. When the attendant answers the call in the usual manner, the subscriber at the substation A' gives her the number of the desired substation at the main automatic exchange. The operator takes notice that the call is coming in over a trunk not permitted outside service in the main automatic exchange. She then refuses to set up the connection and informs the calling subscriber accordingly.

Should the operator overlook the fact that the call is coming in over a trunk not assigned to outgoing service to the main automatic exchange, she may attempt to complete the connection by inserting the calling plug of a cord CC into the jack of an idle trunk to the main automatic exchange. It is assumed that the trunk comprising conductors 207 and 208 terminating in the jack J⁴ is the trunk selected. Inserting the plug P' into the jack J⁴ allows the cut-off relay 201 to operate from ground on the make contact of spring 206. Switching relay 107 does not energize over its lower winding because of the ground on both ends of this winding. The attendant throws the key K' to the dialling position in an attempt to dial the number of the desired substation. It will be remembered, however, that when the plug P is inserted in a jack, such as J', in answering a call, the discriminating relay 103 is maintained inoperative because of the ground on the working contact of spring 89. Therefore, no ground potential is supplied

to the discriminating conductor 153'. Consequently, no circuit will be closed at spring 146 and its working contact for the upper winding of relay 107. Since neither the 5 upper winding nor the lower winding of relay 107 is energized, relay 107 does not operate and the actuation of the dial D is of no avail, since the talking strands of the cord circuit are disconnected from the tip 10 and ring of the plug P' at the armatures 125 and 126, respectively. The circuit for the supervisory lamp L⁴ is not closed at armature 124, and the failure of the lamp L⁴ to light indicates to the attendant that 15 the attempted call is not being completed, whereupon she will recall the fact that service is to be denied and will inform the calling subscriber accordingly.

In accordance with a special feature of 20 this invention, it will now be shown how it is impossible for the attendant to complete the unauthorized connection in question, should she deliberately attempt to complete such a connection. In the foregoing para- 25 graph, it is shown how the unauthorized connection being attempted cannot be completed by inserting the answering plug P and calling plug P' of the cord circuit CC into the jacks J' and J⁴, respectively, the 30 reason being that relay 103 is short circuited by the ground at the spring 89 when plug P is in jack J'; and, therefore, no ground is supplied to conductor 153 to energize relay 107 when the dialling key is depressed. 35 Consequently, the connection is held open at armatures 125 and 126 of relay 107.

It will again be assumed that the subscriber at substation A has called the attendant by dialling the digit 9 and that the attendant has answered by inserting the plug P into the jack J' and that the attendant has received the number of the desired sub- 40 station. In order to call the desired sub- station at the main automatic exchange, the attendant may attempt to use a second cord. 45 By inserting the answering plug of the second cord into any idle outgoing trunk jack, such as J, and inserting the calling plug of the second cord circuit into an idle trunk to the main automatic exchange and by dialling the number of the called substation, the attendant may obtain connection with the called substation in the ordinary manner. The relay in the second cord circuit similar 50 to relay 103 energizes in series with relay 76, and the relay similar to relay 107 operates in response to the actuation of the dial key from ground on the conductor similar to 153'. The attendant may now throw both 55 the key K and the listening key of the second cord circuit in the listening position in an attempt to complete the connection by means of the two cord circuits through the attendant's head set. This attempt will fail, 60 however, because, as soon as the listening 65

keys of the two cords are thrown, the ground on the spring 89 is conducted by way of the sleeve of jack J', sleeve of plug P, working contact of spring 139 and said spring, to the associated common conductor 70 and through the spring and its working contact of the second cord circuit similar to spring 139 and its working contact to the winding of the relay in the second cord circuit similar to relay 103. This relay is thus 75 short circuited and deenergized. Ground is removed from the conductor in the second cord circuit similar to 153, and the relay in the second cord circuit similar to relay 107 is deenergized. The connection is then 80 opened at the armatures of this relay in the second cord circuit similar to relay 107. The resulting condition soon becomes apparent to the attendant who, realizing that the unauthorized connection cannot be completed, 85 informs the calling subscriber accordingly.

There is also another reason why the above attempted connection cannot be completed 90 in that only one cord circuit can be connected to the attendant's head set at one time. This feature will be explained hereinafter in connection with another call.

In the foregoing, it has been shown how 95 connections are completed from a restricted substation, to an individual common battery telephone, or to a substation in the common battery manual switchboard. It has also been shown that it is impossible to complete 100 a call from a restricted substation to the main automatic exchange. In the following description, it will be shown how calls originating at either a common battery manual switchboard or a common battery telephone may be extended to any substation 105 in the private automatic exchange; and also how calls originating at the main automatic exchange may be extended to any of the private automatic substations allowed unrestricted service. 110

To complete a call from a common battery manual telephone, such as B, to any of the private automatic substations, the subscriber at substation B removes his receiver to call the operator. Removing the receiver at the 115 substation B closes a bridge across the conductors 217 and 218, thereby completing a circuit for the line relay 211 by way of armatures 212 and 213 and their resting contacts, the upper and lower windings of the line relay 211, to ground and battery, respectively. The line relay 211 energizes and completes a circuit for the lamp L⁶ at armature 214. In response to the lighting of lamp L⁶, the attendant inserts the answering plug P of a cord CC into the jack J⁵, and throws the key K in the listening position. Throwing the key K in the listening position bridges the attendant's head set across the talking strands 153 and 154 of the cord 120 125 130

CC. Inserting the plug P into the jack J⁵ closes a circuit for the discriminating relay 103 and the cut-off relay 210 in series. Relay 210 operates and opens the circuit for the line relay 211 at its armature 212 and 213. The line relay 211 deenergizes, thereby extinguishing the lamp L⁶. Relay 103 operates and places ground potential on the discriminating conductor 153' at armature 116, and bridges the battery feed relay 102 across the talking strands 154 and 153 of the cord circuit at armatures 117 and 118. Relay 102 operates and opens the circuit for the supervisory lamp L³ at the armature 115. Talking battery is furnished to substation B through relay 102.

The attendant now converses with the calling subscriber to obtain the number of the private automatic substation with which connection is desired. It will first be assumed that the substation with which connection is desired is the unrestricted substation A, having the multiple jack J² at the attendant's switchboard. Before inserting the plug P' into the jack J², the attendant will touch the tip of the plug P' to the sleeve of the jack J² to determine whether the substation A is busy or idle. If the substation A is busy, a circuit will be closed from ground on conductor 66', conductor 66, sleeve of jack J², tip of plug P', normally closed springs controlled by armature 125, through the winding of the busy-test relay 109 to battery. Relay 109 operates and closes a circuit at armature 129 for the tertiary winding of the inductance coil of the attendant's head set. The sudden building up of current in the tertiary winding induces a momentary flow of current in the secondary winding of the induction coil, which produces a click in the attendant's receiver. This click in the attendant's receiver indicates that the substation A is busy. Assuming that the substation A is idle, no click will be heard in the attendant's receiver and the attendant will proceed to insert the plug P' into the jack J². A circuit will be closed from ground by way of the lower winding of the relay 107, sleeve of the plug P', sleeve of jack J², conductor 66, conductor 66', winding of the switching relay 6 of the line switch LS, resting contact of armature 15 and said armature, winding of stepping magnet 8 to battery. On account of a mechanical interlocking device controlled by the armature of the line relay 7, which is now normal, the armatures of the switching relay 6 are attracted only enough to disconnect the line of the substation A from its normal battery and ground connections in the line switch LS. Switching relay 107 operates over its lower winding and closes a circuit for the supervisory lamp L⁴; connects the talking strands of the cord circuit to the tip and ring of the plug P',

respectively; and closes a holding circuit for its upper winding, as previously described. To signal the subscriber at the substation A, the attendant intermittently throws the key K' to the ringing position 76 and back to normal, thereby ringing the bells at the substation A.

When the subscriber at the substation A removes his receiver, a bridge is placed across the line conductors 4 and 5, thereby completing a circuit for the battery feed relay 106 of the cord circuit CC. Relay 106 operates and opens the circuit for the supervisory lamp L⁴ at its armature 123. Relay 106 also supplies talking battery to the 80 called substation A. The extinguishing of the lamp L⁴ indicates to the attendant that the called subscriber at substation A has answered and that conversation is being held.

When the conversation is completed, both subscribers will replace their receivers. Replacing the receiver at substation A opens the bridge across the line conductors 4 and 5 which opens the circuit for the battery feed relay 106. Relay 106 deenergizes and again closes the circuit for the supervisory lamp L⁴. The replacing of the receiver at substation B opens a bridge across the line conductors 217 and 218, thereby opening the 95 circuit for the battery feed relay 102. Relay 102 deenergizes and again closes the circuit for the lamp L³. The lighting of lamps L³ and L⁴ indicates to the operator that she may pull down the connection.

It is now assumed that the subscriber at substation B desires connection with the restricted substation A', having the multiple jack J³ at the attendant's switchboard. The subscriber at substation B lifts his receiver to call the operator and gives her the number of the substation with which connection is desired. Before inserting the plug P' into the jack J³, the attendant tests the line in the manner described above. Assuming the substation A' is idle, the attendant inserts the plug P' into the jack J³. A circuit is again closed from ground by way of the lower winding of the relay 107, sleeve of plug P', sleeve of jack J³, conductor 71, conductor 71', the switching relay and stepping magnet of the line switch LS' to battery. The switching relay of the line switch LS' operates to disconnect the line conductors 2 and 3 from their normal battery and ground connections in the line switch LS' in the manner described hereinbefore. The lower winding of the switching relay 107 is not energized at this time because of the ground on the working contact of the 110 springs 91 of the jack J³.

The attendant now signals the subscriber at substation A' by intermittently throwing the key K' to the ringing position. As soon as the key K' is thrown to the listening po-

sition, a circuit is closed from ground on the discriminating conductor 153' by way of the working contact of spring 142 and said spring, through the upper winding of 5 the relay 107 to battery. Relay 107 now energizes and immediately closes a holding circuit for itself at armature 127, and prepares the cord circuit as described hereinbefore. When the subscriber at substation A' removes his receiver, a bridge is placed across 10 the line conductors 2 and 3, thereby closing a circuit through the battery feed relay 106. Relay 106 operates and opens the circuit for the supervisory lamp L⁴.

15 When the conversation is completed, both subscribers will replace their receivers and the attendant will receive the disconnect signal by the lighting of lamps L³ and L⁴, whereupon she proceeds to pull down the 20 connection.

Calls may also be extended from any of 25 the subscribers of the common battery manual switchboard to the subscribers of the private automatic exchange. To complete this kind of a connection, the subscriber 30 of the common battery manual switchboard first calls the manual operator by removing his receiver. In response to the usual signal, the manual operator answers the call and 35 proceeds to complete the connection by inserting the calling plug of one of her cords into the jack of an idle trunk extending to the private automatic exchange. Assuming this trunk to be the one comprising conductors 229 and 230, the manual operator inserts 40 the calling plug of her cord into the jack J'. The cut-off relay 310 is energized from battery on the sleeve of the operator's cord and operates to open the circuit of the drop-signal relay 311 at armature 312. Since there is ground and battery potential 45 present on the tip and ring of the manual operator's cord, respectively, inserting the plug of the operator's cord into jack J' supplies 50 current to conductors 229 and 230, and closes a circuit for the relay 253. Relay 253 operates and closes a circuit for the line relay 251 and the polarized relay 252 in series at armature 258. Relay 251 operates 55 and closes a circuit for the call signal lamp L⁷ at armature 256. The flow of current in the polarized relay 252 at this time is in such a direction so as to maintain relay 252 inoperative.

55 In answer to the lighting of the lamp L⁷, the attendant inserts the answering plug P of the cord CC into the jack J⁶. As a result, a circuit is closed for the discriminating relay 103 and the cut-off relay 250 in series. 60 Cut-off relay 250 operates and disconnects the line relay 251 from the conductors 227 and 228 at armatures 254 and 255, respectively. Line relay 251 deenergizes and extinguishes the lamp L⁷. The discriminating relay 103 operates and places ground on the

discriminating conductor 153' at armature 116 and bridges the battery feed relay 102 across the talking strands 153 and 154 of the cord CC in the usual manner. Battery feed relay 102 now operates and opens the circuit 70 for the supervisory lamp L³ at armature 115. Ground and battery are now supplied through the battery feed relay 102 to the conductors 227 and 228, the reverse of that supplied through the line relay 251. The 75 current through the polarized relay 252 is now in the direction to cause its operation. The polarized relay 252 operates and short circuits the greater portion of the winding of relay 253 at the armature 257 and its 80 working contact. As a result, the current in the conductors 229 and 230 is sufficiently increased to operate the usual supervisory signal in the operator's cord, and thus signal the manual operator that the attendant at 85 the private automatic exchange has answered. The manual operator now informs the attendant at the private automatic exchange of the connection desired, and the attendant proceeds to complete the connection to the 90 desired substation of the restricted or the unrestricted class, as the case may be, in the manner described in the foregoing description.

At the termination of the conversation, 95 both the automatic subscriber and the common battery manual subscriber will replace their receivers. Replacing the receiver at the automatic substation opens the bridge across the talking strands 151 100 and 150, thereby opening the circuit of the battery feed relay 106. Relay 106 deenergizes and closes a circuit for the supervisory lamp L⁴. When the common battery manual subscriber replace his receiver, the manual 105 operator receives the usual signal and proceeds to remove the plug from the jack J'. This opens the circuit for the relay 253. Relay 253 deenergizes and opens the circuit for the battery feed relay 102. Relay 102 de- 110 energizes and closes the circuit for the supervisory lamp L³. The lighting of both lamps L³ and L⁴ is the disconnect signal to the attendant in response to which she pulls down the connection.

Calls originating at the main automatic exchange may also be extended to any of the private automatic substations having unrestricted service, but cannot be extended 115 to those private automatic substations having restricted service. It will now be assumed that a subscriber at the main automatic exchange wishes to have a connection established with a substation in the unrestricted class at the private automatic exchange, such as substation A. To originate the call, the subscriber at the main automatic exchange removes his receiver and dials the directory number assigned to the private automatic exchange. The call will be ex- 120 125 130

tended in the usual manner through a line switch, one or more selectors, and to a rotary connector in the banks of which access is had to trunks extending to the private automatic exchange. After the subscriber at the main automatic substation has finished dialing the last digit, the rotary connector automatically selects an idle trunk extending to the private automatic exchange and supplies ringing current thereto. Assuming the trunk comprising conductors 207 and 208 accessible at the bank contacts 310, 311, and 312, is the trunk selected, the ring-down relay 202 becomes energized by the ringing current and locks up mechanically by an interlocking arrangement (not shown) controlled by the armature of the cut-off relay 201. Ground supplied to contact 311 by the rotary connector completes a circuit for the switching relay of the line switch LS². The switching relay operates sufficiently to disconnect the trunk conductors 207 and 208 from the line switch LS². The ring-down relay 202 operates and closes a circuit for the lamp L⁵ at armature 205. The lighting of lamp L⁵ signals the attendant who answers the call by inserting the answering plug P of the cord into the jack J⁴ and throwing the key K into the listening position in the usual manner. The subscriber at the main automatic exchange may now inform the attendant of the substation with which connection is desired. Inserting the plug P into the jack J⁴ closes a circuit for the cut-off relay 201 and the discriminating relay 103 in series. Relay 103 is prevented from operating on account of the additional ground on the sleeve of jack J⁴ at the working contact of spring 206, which places a ground on both ends of the winding of relay 103. The cut-off relay 201 operates and opens the circuit for the call signal lamp L⁵ at armature 203, and also unlocks the armatures of relay 202, allowing relay 202 to fall back to normal. Cut-off relay 201 also disconnects trunk conductor 208 from relay 202 and connects it to the ring of the jack J⁴ at armature 204. Since it has been assumed that the private automatic substation with which connection is desired is the substation A, the attendant will insert the calling plug P' of the cord into the multiple jack J². This closes a circuit for the switching relay 107 and the switching relay 6 of the line switch LS in series. The switching relay 6 operates sufficiently to disconnect the line conductors 4 and 5 from the line switch LS, as described hereinbefore. Switching relay 107 operates to complete the circuit for the supervisory lamp L⁴ and to connect the talking strands of the cord circuit CC to the tip and ring of the plug P', respectively, as has been previously described. The attendant signals the subscriber at substation A by means of the key K'.

When the subscriber at substation A removes his receiver, a direct current bridge is placed across the conductors 4 and 5, thereby closing a circuit for the battery feed relay 106. Relay 106 operates to open the circuit for the supervisory lamp L⁴. The subscribers may now hold conversation.

When the conversation has been completed, both subscribers will replace their receivers. The replacing of the receiver at substation A opens the circuit for the battery feed relay 106. Relay 106 deenergizes and again closes the circuit for the supervisory lamp L⁴. The lighting of the lamp L⁴ for this type of call, signals the operator to pull down the connection, whereupon she removes the plugs P and P' from the jacks J⁴ and J², respectively. The replacing of the receiver at the main automatic substation releases the automatic switches in the usual manner.

In previous paragraphs, it has been shown how it is impossible to establish a connection between a restricted substation, such as A', and a substation at the main automatic exchange. Similarly, it is impossible to establish a connection from a substation in the main automatic exchange to a restricted substation at the private automatic exchange. To briefly describe the result of an attempt to complete an unauthorized connection, it will be assumed that a connection from the main automatic exchange to the restricted substation A' is requested, and that the attendant attempts to complete this connection by inserting the plug P into the trunk jack J⁴ terminating the trunk over which the call is assumed to be coming, and by inserting the plug P' into the jack J³. The discriminating relay 103 is maintained inoperative on account of the ground placed on the sleeve of jack J⁴ at the working contact of spring 206 when the plug P is inserted in jack J⁴. For this reason, no ground potential is supplied to the conductor 153. The lower winding of the switching relay 107 is not energized because of the ground supplied to the sleeve of jack J³ at spring 91 and its working contact, when the plug P' is inserted into jack J³; nor is it possible to energize the upper winding of relay 107 because of the absence of ground on the discriminating conductor 153. The connection between the two subscribers is therefore held open at the armatures 125 and 126 of the switching relay 107.

There is another manner in which the attendant may attempt to complete the unauthorized call. The attendant may insert the answering plug P into the jack J⁴ and the answering plug of a second cord into the jack J³ and then simultaneously throw the key K and the corresponding key of the second cord in the listening position in an effort to complete the call through the op-

erator's head set. This attempt will fail, however, because only one cord can be connected to the head set at one time. The relay 108 in the operator's head set has a high resistance winding. The lower winding of the lock-up relay of each cord, such as the relay 101 of the cord circuit CC, is a low resistance winding. As stated before, the lock-up relay 101 is held up by its lower winding which is in series with the winding of relay 108. The resistance of the winding of relay 108 and the resistance of the lower winding of the lock-up relays of the cords are such that while one lock-up relay will hold up in series with relay 108 of the attendant's head set, two lock-up relays in parallel will not hold up in series with the relay 108. When the operator throws two keys in the listening position simultaneously, the two corresponding lock-up relays will pull up from ground on the resting contact of armature 128 of relay 108. The two lock-up relays operate and close the circuit for the relay 108 at the armatures corresponding to armature 113. Relay 108 energizes and opens the initial energizing circuit for the two lock-up relays at its armature 128. Since the two lock-up relays are in parallel, each lock-up relay receives an insufficient current through its lower winding to hold itself operated. The two lock-up relays therefore drop back and open the circuit for relay 108 at the armatures corresponding to armature 113. Relay 108 drops back and again closes the initial energizing circuit for the two lock-up relays at armature 128. This action of the lock-up relays repeats itself in a buzzer-like manner until the attendant, seeing that no connection is being completed, restores the two listening keys, or until one of the two lock-up relays falls back a sufficient length of time before the other opens its circuit at its armature corresponding to armature 113, to allow the latter lock-up relay to lock up directly in series with the relay 108. Only one cord, however, is then connected to the head set, which will immediately become evident to the attendant. It is then apparent to the operator that the unauthorized call cannot be completed, whereupon she will inform the calling subscriber accordingly.

A connection may be established from any of the subscribers at the main automatic exchange, to any of the individual common battery substations, or to any of the substations of the common battery manual switchboards. Likewise, connections may be established from substations of the common battery manual switchboard to any of the substations at the main automatic exchange, or with any of the individual common battery substations; or from the individual common battery substations to substations of the main automatic exchange, or substations in the common battery manual switchboard; or between any two individual common battery substations. The operations performed and the sequence thereof, and the functions of the separate circuits in completing any of the above mentioned connections is evident from the descriptions of the various operations given in the foregoing paragraphs.

Long distance service is also available to the individual common battery telephones, to the substations at the common battery manual switchboards, or to the unrestricted substations of the private automatic exchange. Any of these substations wishing a long distance connection will call the attendant at the private automatic exchange and inform her accordingly. The attendant then calls the long distance operator at the main automatic exchange over a trunk such as the trunk comprising conductors 207 and 208, in turn informing the long distance operator of the connection desired. When the long distance operator at the main automatic exchange has established connection with the distant substation, she recalls the attendant at the private automatic exchange over a similar trunk, such as the one comprising conductors 207 and 208. The attendant at the private automatic exchange now completes the connection by recalling the subscriber who desires this long distance connection.

In establishing a long distance call from a subscriber in the manual exchange, it may be desirable to hold the set-up between the manual operator and the private automatic exchange during the time that the long distance operator at the main automatic exchange is extending the call. Then as soon as the long distance operator notifies the attendant that the desired long distant connection has been obtained, the attendant need only resignal the manual operator. A flash key K² is provided for this purpose. Assuming then that the plug P is inserted in the jack J⁶, and that the attendant at the private automatic exchange wishes to flash the operator at the common battery manual switchboard to which the trunk comprising conductors 229 and 230 extends. The attendant will throw the key K in the listening position and will intermittently throw the key K² to the flashing position. Normally, when the plug P is in the jack J⁶, the discriminating relay 103 is held operated in series with the sleeve relay 250. Battery is then supplied through the battery feed relay 102 to conductors 227 and 228 in the proper direction to operate the polarized relay 252. As described above, the supervisory signal in the manual operator's cord is responsive to the action of the polarized relay 252. When the key K² is operated to the flashing position, relay 103 is intermittently short circuited by ground at the work.

ing contact of the springs 132 by way of spring 139 and its working contact. Relay 103 energizes and deenergizes responsively, and, as a result, intermittently connects and disconnects the battery feed relay 102 from the conductors 227 and 228. The polarized relay 252 pulls up and drops back in synchronism with the operation of the key K² and thereby causes the flashing of the supervisory lamp in the manual operator's cord.

During the flashing period, relay 108, being slow to release, is maintained operated from ground on the working contact of spring 131 and said spring. The first time the holding circuit of the lock-up relay 101 is opened at spring 131 and its resting contact, relay 101 drops back. Since its initial energizing circuit is held open at armature 128, relay 101 is maintained deenergized during the flashing period. This prevents the impulses produced by flashing from being heard in the attendant's receiver.

Various other uses of this flashing key will suggest themselves to those skilled in the art.

25 What is claimed is:

1. In a telephone system, a branch exchange, restricted and non-restricted lines in said branch exchange, means for establishing a connection between any of said lines, restricted and non-restricted trunks terminating at said branch exchange, means for establishing a connection between any of said trunks and any of said non-restricted lines, means for establishing a connection between any of said non-restricted trunks and any of said lines or said trunks, and means for preventing a connection between a restricted line and a restricted trunk.

2. In a telephone system, a branch exchange including a group of lines, a second group of lines, means including a cord circuit for establishing connections between any of the lines of the first group; between certain of the lines in the first group and any of the lines in the second group; and between certain of the lines in the second group and any of the lines in the first group, and means for preventing the other lines in the first group both from calling or being called by the other lines in the second group.

3. In a telephone system, an operator's switchboard, restricted trunks terminating in jacks at said switchboard, non-restricted trunks terminating in other jacks at said switchboard, a cord circuit including a calling plug and an answering plug and having its talking conductors normally disconnected from said calling plug, a key in said cord circuit, means in said cord circuit for connecting the talking conductors of said cord circuit to said calling plug upon insertion of said calling plug into a non-restricted trunk jack, means in said cord circuit for connecting the talking conductors of said cord circuit to said calling plug upon inser-

tion of said answering plug into a non-restricted trunk jack and actuation of said key, and means for preventing the connection of the talking conductors of said cord circuit to said calling plug upon insertion of both of said plugs into restricted trunk jacks.

4. In a telephone system, trunk lines terminating in jacks, a cord circuit having its talking conductors normally disconnected from the calling plug thereof, a key in said cord circuit, means for connecting said talking conductors to said plug responsive to the actuation of said key whenever said plug has been inserted in the jack of one of said trunk lines, and means for preventing the connection of said talking conductors to said plug responsive to the actuation of said key whenever said plug is in the jack of another of said trunk lines.

5. In a telephone system, an attendant's position, a trunk line terminating in a jack, a cord circuit, a plug whose talking terminals are normally disconnected from said cord circuit, a relay for connecting said talking terminals to said cord circuit, a key and means for energizing said relay upon insertion of said plug into said jack or upon the operation of said key independent of the insertion of the plug.

6. In a telephone system, an operator's switchboard, a first trunk line terminating in a jack, a second trunk line terminating in a jack, a cord circuit having a plug normally disconnected from said cord circuit, a relay in said cord circuit, means for actuating said relay whenever said plug is inserted into the jack of said first trunk line, means for preventing the actuation of said relay whenever said plug is inserted into the jack of the said second trunk line.

7. In a telephone system, an attendant's switchboard, trunk lines terminating in jacks, a cord circuit having a calling plug and an answering plug, and having its talking conductors normally disconnected from said calling plug, a relay having two windings for connecting the talking conductors of said cord circuit to said calling plug, means for energizing said relay over one winding upon insertion of said calling plug into a trunk jack, means for preparing the circuit of the other winding of said relay upon insertion of said answering plug in a trunk jack, and manually operated means for energizing said relay over the said other winding provided said answering plug has been inserted in a trunk jack.

8. In a telephone system, an operator's position, a cord circuit including a plug, a relay in said cord circuit having a winding connected to the sleeve terminal of said plug and contacts in the talking conductors of said cord circuit, a trunk line terminating in a jack at said operator's position, another trunk line terminating in a second jack at

5 said operator's position, means for energizing the winding of said relay upon insertion of said plug into said first jack, and means for short circuiting the winding of said relay upon insertion of said plug into said second jack.

9. In a telephone system, a cord circuit including a plug, a relay in said cord circuit connected to the sleeve terminal of said plug, 10 a line terminating in a jack, a relay connected to the sleeve terminal of said jack, a second line terminating in a second jack, a relay connected to the sleeve terminal of said second jack, means for operating the relay in said cord circuit in series relation with the relay connected to the sleeve terminal of said first jack upon insertion of said plug into said first jack, and means for short circuiting the relay in said cord circuit and 15 operating the relay connected to the sleeve terminal of said second jack upon insertion of said plug into said second jack.

10. In a telephone system, a restricted line, a non-restricted line, a cord circuit for 20 extending a connection to either of said lines, said cord circuit having a calling end, a normally closed bridge in said cord circuit, a normally open bridge in said cord circuit, means for opening said first bridge and closing said second bridge, and means 25 for disabling said first means depending on whether said cord circuit is connected to said restricted line or said non-restricted line.

11. In a telephone system, a first trunk 30 line leading to an automatic exchange, a second trunk line leading to a manual exchange, a cord circuit for extending a connection to either of said trunk lines, a normally closed bridge including a relay in said cord circuit, a normally open bridge including a second relay in said cord circuit, means 35 for opening said first bridge and closing said second bridge depending on whether said cord circuit is connected to said first trunk line or said second trunk line.

12. In a telephone system, an operator's position including a head set and a plurality of cord circuits, means including a key, in each of said cord circuits for connecting said cord circuit to said head set, and means at said operator's position for preventing more than one of said cord circuits being connected to said head set at the same time.

55 13. In a telephone system, an operator's position including a head set and a plurality of cord circuits, means including a key, for connecting any one of said cord circuits to said head set and for preventing a plurality of said cord circuits being simultaneously connected to said head set.

14. In a telephone system, an operator's position including a head set, a cord circuit, a relay in said cord circuit for connecting 60 said head set to said cord circuit, manually

operated means including a key, for closing an initial energizing circuit for said relay and a locking circuit for said relay, and a second relay included in said locking circuit for opening said initial energizing circuit. 70

15. In a telephone system, a trunk line terminating in a jack, a cord circuit including a plug, a normally open battery feed bridge in said cord circuit, means for closing said bridge upon insertion of said plug 75 into said jack, and operator-controlled means for including a listening key for disconnecting said bridge and reconnecting it at will.

16. In a telephone system, a trunk line terminating in a jack, a cord circuit including a plug, a battery feed bridge in said cord circuit normally disconnected from the talking conductors of said cord circuit, means for connecting said bridge across said 80 trunk line upon insertion of said plug into said jack, and operator-controlled means including a listening key for disabling first 85 said means for disconnecting said bridge and reconnecting it at will. 90

17. In a telephone system, a cord circuit comprising talking strands and having a plug at each end, said strands being normally open, and means controlled through either plug for closing said strands. 95

18. In a telephone system, a plurality of groups of lines, each group containing restricted and unrestricted lines, a cord circuit for connecting lines of one group with those of another, said cord circuit including talking conductors and having a plug at each end, said plugs being normally in inoperative relationship, and means for bringing them into operative relationship, said means being effective when either of said plugs is 100 associated with a non-restricted line and the other plug is associated with any line and being ineffective when both plugs are associated with restricted lines. 105

19. In a telephone system, a restricted and a non-restricted line, restricted and non-restricted trunks, a cord circuit for connecting said lines with said trunks, a plug for said cord circuit, talking strands in said cord circuit, said strands being normally 110 disconnected from said plug, a relay arranged to connect said strands to said plug, means for energizing said relay when said cord circuit connects a restricted line with a non-restricted trunk, or a non-restricted line 115 with either a restricted or non-restricted trunk, and means for preventing energization of said relay when said cord circuit connects a restricted line and a restricted trunk. 120

20. In a telephone system, subscribers' lines, trunk lines, means for interconnecting any of said lines with certain of said trunks, means for preventing the extension of calls from certain subscribers' lines to certain 125 130

trunk lines, and means for preventing the extension of calls from certain trunk lines to certain subscribers' lines.

21. In a telephone system, a subscriber's line, means for extending the line to a telephone switchboard over either of two paths, a cord circuit for use in extending connections from said line to other lines terminating at said switchboard and also from said line to trunks extending to a distant exchange, the talking strands of the cord being normally open, a relay controlled over a connected one of said last mentioned lines but independent of control over a connected one of the trunks for closing said talking circuit, additional means controlled over one only of said two paths for controlling said relay, and means for rendering said last mentioned path inaccessible to said subscriber's line.

22. In a telephone system including manual substations and restricted and unrestricted automatic substations, an automatic switch accessible to the automatic substations, two groups of trunks extending from the switch and terminating in jacks at an operator's switchboard, a cord circuit for extending connections from said jacks to said manual substations and from certain of

said jacks to a distant exchange, means for rendering the cord circuit ineffective to extend a connection from the remaining jacks to the distant exchange, and means for rendering the first mentioned jacks inaccessible to the restricted substations. 30

23. In a telephone system, an operator's position including a head set and a plurality of cord circuits, means including a key in each of said cord circuits for connecting said cord circuit to said head set, means at 40 said operator's position for preventing more than one of said cord circuits being connected to said head set at the same time, and a common key for disabling the connecting means. 45

24. In a telephone system, an operator's position including a head set and a plurality of cord circuits, means including a key and a self-locking relay for connecting any one of said cord circuits to said head set and 50 for preventing a plurality of said cord circuits being simultaneously connected to said head set, and a flashing key having contacts in the self-locking circuit of said relay.

In witness whereof, I hereunto subscribe 55 my name this 19th day of March, A. D. 1925.

THOMAS F. CROCKER.
